UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS.

COIN-DELIVERY MACHINE.

1,099,687.

Specification of Letters Patent.

Patented June 9, 1914.

Application filed February 6, 1913. Serial No. 746,508.

To all whom it may concern:

Be it known that I, EDWARD J. BRANDT, a citizen of the United States, and resident of Watertown, in the county of Jefferson and State of Wisconsin, have invented certain new and useful Improvements in Coin-Delivery Machines; and I do hereby declare that the following is a full, clear, and exact description thereof.

10 My invention consists in what is herein particularly set forth with reference to the accompanying drawings and pointed out in the claims of this specification, its object being to prevent sticking and to facilitate the delivery of coins from compartments of coin-delivery machines of the type now generally known to the trade and public as "Brandt automatic cashiers." This object is attained by offsetting the lower discharge 20 end of each coin-compartment in such a manner as to provide for relieving the lowermost coin or coins in said compartment from much of the weight of the coins higher up in the same column.

25 Figure 1 of the drawings represents a partly sectional elevation of one of my improved coin compartments and contents, the section being indicated by line 1—1 in the next described illustration. Fig. 2, a similar 30 view of which the section is indicated by line 2—2 in Fig. 1.

Referring by numerals to the drawings, 3 indicates one of what is generally a group of coin-compartments in a tray that may be 35 either a fixed or removable part of a coin-delivery machine of the type above noted. The delivery-end of the compartment is laterally offset, as shown in Fig. 1, and provided with the usual coin-supporting ledges 40 between which a spring-controlled coin pusher 5 has play, this pusher being in pivotal connection with an actuating lever 6. The offsetting of the compartment, as aforementioned results in a tilt of the major portion of 45 the coin column therein, the tilt being above any predetermined number of the coin in said column, and thus the weight of the superimposed coin is divided between the incline opposing surface 7 of said compartment and the underneath coin, the prepon-

derance of said weight being upon said inclined surface of the aforesaid compartment. Hence it will be readily understood that the coin in the path of the pusher 5 is not liable to stick or otherwise materially oppose the 55 action of said pusher, this being the important advantage in the use of machines to which my improvements relate.

It is to be observed that the amount of frictional contact of the lowermost tilted coin 60 of the column upon the coin next below is slight, and the descent of said tilted coins along the inclination of the offset portion of the coin compartment is unimpeded.

I claim:

1. In a coin holder for coin delivery machines, and in combination, a member having sides and back walls fashioned to hold and guide a stack of coin, a supporting ledge at the base of the holder, means for ejecting 70 the lowermost coin from the holder, and a fixed projecting coin supporting part in the holder at the lower portion thereof above the said base for supporting in part the stack of coin above the base, the interior surfaces 75 of the walls of said member being smooth and unobstructed throughout above the said projecting coin supporting part.

2. A coin delivery machine coin compartment, said coin compartment having an intermediate portion arranged at an angle to the upper and lower portions of the compartment to provide for a tilt of the major portion of the coin column, and a division of its weight upon the inclination 85 of said compartment and the lowermost remainder of said column.

3. A coin compartment comprising upper and lower portions, and an intermediate inclined portion to provide for a tilt of the 90 major portion of the coin column, and a division of its weight upon the inclination of said compartment and the lowermost remainder of said column.

4. In a coin holder for coin delivery machines, and in combination, a member having sides and back walls fashioned to hold and guide a stack of coin, a supporting ledge at the base of the holder, means for ejecting the lowermost coin from the holder, and a 100

fixed projecting coin supporting part in the
holder above the said base having a support-
ing face inclined inwardly whereby the coin
may pass promptly from the projection onto
5 the base, substantially as described.

In testimony that I claim the foregoing I
have hereunto set my hand at Watertown

in the county of Jefferson and State of Wis-
consin in the presence of two witnesses.

EDWARD J. BRANDT.
